PERFORATED SAMPLE CARD

Sydney E. Bender, Brooklyn, N. Y.

Application March 5, 1935, Serial No. 9,520

8 Claims. (Cl. 206—82)

The present invention relates to sample cards in general, and what may be termed perforated sample cards.

The prime object of this invention is the process of producing in a most inexpensive way, an attractive sample card with samples appearing within perforations.

Another object of this invention is to provide a sample card with marginal or otherwise arranged perforated sample carrying elements in strip form, which not only is easily and inexpensively manufacturable, but which is very attractive in appearance and practical in use, since the samples may be observed within the perforations, by either placing under one of their faces a suitable background, such as human flesh of the hand or finger, or materials of different colors, or by looking through the perforations, whereby the samples may be scrutinized as to their respective colors, qualities, structure, transparency and many other properties.

The foregoing and still further objects will become more fully apparent from the ensuing description and from the accompanying drawing forming part of my disclosure, but which by no means are intended to limit me to the actual constructions illustrated.

In the drawing, Figure 1 represents a portion of a sample card equipped with my sample carrying elements in one of its preferred forms.

Figure 2 is a cross-sectional view taken on lines 2—2 of Figure 1.

Figure 3 illustrates a perforated sample carrier, preparatory to the application of various samples thereto.

Figure 4 illustrates the sample carrier partially equipped with the sample and separated and cut to form perforated sample carrier elements.

Figure 5 illustrates a portion of a support employed for the attachment of the sample carrier.

Figure 6 illustrates a portion of a finished sample carrier with several elements shown.

Figure 7 is a modified form of a portion of a sample card.

Figure 8 is a cross-sectional view taken on lines 8—8 of Figure 7.

Figure 9 is an attachable supporting member adapted to be secured to the margin of a plain sample card, as shown in Figures 7 and 8, and

Figures 10, 11, 12 and 13 illustrate modified forms of my sample card.

Referring now to the figures, numeral 10 denotes a carrier which is provided with a plurality of perforations 11, arranged in groups of any desired number.

In Figure 3, there are shown such groups, each consisting of two vertical rows of perforations arranged parallel to one another and spaced equally, so that at least two adjacent perforations, constituting portions of horizontal rows of each group, form a pair. There are shown several such groups, adjacent to one another, and below one another, each group being limited by dot and dash lines 12 and 13. Each pair of perforations of each group is covered by one strip of sample material, shown in full lines at 14 and 15 at the right-hand end of Figure 3, and indicated in broken lines continuing over carrier 10. The sample strips are preferably glued to the body of the carrier, so that the material portion coinciding with or covering the perforations is free.

When all the horizontal rows of perforations of all groups are covered with different materials, the carrier is then cut with a die in the manner illustrated in Figure 4, whereby not only the carrier body itself, but also the sample material, is cut. By thus stamping the carrier, each group is separated in two individual units 16, each unit consisting of six perforated elements 17. Each element carries a different piece of material. When the units are finished, they are applied and attached, with the sample face, to a pre-cut support, backing or covering as shown at 18 in Figure 5. The marginal elements 19 of the support correspond in shape and perforations to the shapes and perforations of elements 17. The latter are so placed against one face of the support that the shapes and perforations of both exactly register, as clearly seen in the finished article in Figure 1. The attachment of each unit to the sample support is accomplished by an adhesive action, and I so prepare the carrier that the glue applied thereto will suffice for the secure attachment of each unit to the support.

In the modified form shown in Figures 7, 8 and 9, an auxiliary supporting member is employed, as indicated in Figure 9. This supporting member corresponds in general outlines to a finished unit, but possesses a wider end margin 20, from which extend perforated elements 21. The carrier in this modification may be of the same shape as support 20, (as shown at 20' in Figure 8), in which case, the groups of perforations are spaced somewhat wider apart. The application of the sample materials to the carrier is accomplished in the same manner as previously described, but instead of attaching the finished unit to a support, as shown at 18, the carriers are secured to a supporting member 20, and the sup-

porting member 20 is then attached to the edge of a sample card 21, as shown in Figures 7 and 8.

In Figures 1 to 8, sample carrying elements are shown in the form of rings. In Figures 10, 11 and 5 12, the sample carrying elements assume different shapes and proportions, and in Figure 13, the carrying elements comprise squares. In all of the modified forms, the construction of the elements are the same, and are constructed in the 10 same manner as described previously in connection with Figures 1, 2, 3 and 4, or in the manner shown in Figures 7, 8 and 9. In each case, however, the elements either form marginal extensions of the card or support, integral with the latter, or are permanently attached in rows to the edge of a card. In all structures shown, the frames of the elements are opaque, while the sample material is preferably translucent, thus permitting the observer to look through the material, when desired.

The foregoing description covers sample cards in which the sample material is held by individual elements, separated from one another by what may be termed "scalloping", which, of course, requires relatively costly dies of various patterns, depending upon the shapes of sample elements desired.

By eliminating the employment of special dies for shaping the individual elements, the cost of 30 the sample cards may be considerably reduced, without sacrificing their major practical advantages of facilitating the examination of each sample material in the different ways stated before. Thus, in order to reduce the manufacturing 35 cost, I employ again a carrier 10, having vertical rows of at least two adjacent perforations of any desired shape, such as circles, squares, ovals, etc., which carrier may be composed of any member of vertical double-row 40 groups. Then I attach over all horizontal rows strips of sample material, such as 14 and 15.

Now, instead of "scalloping" the sample-equipped carrier, I follow either of the two possible simple, inexpensive ways of separating the 45 carrier. One way is to cut the carrier into vertical strips, containing a single vertical row of the desired number of perforations. Then I secure to the carrier an un-scalloped, perforated supporting strip, similar to that shown either in 50 Fig. 5 or 9, in the manner previously described, so that the perforations of the carrier register with those of the strip.

However, I may further reduce the cost of manufacture by employing still another modified 55 method. Before separating the carrier sheet 10, after the different sample material strips were secured over the horizontal rows of its perforations, I secure a perforated cover, supporting or backing sheet to the yet uncut carrier, so that 60 all perforations register, and finally I cut the resulting product, without scalloping it, into vertical, simple strips, containing single or multiple rows of the desired number of perforations. Such finished strips may be attached to cards either 65 in the manner shown and described in Figure 8, or may be hinged thereto at their ends or sides, so as to render them free for inspection.

The method employed in producing perforated 70 sample cards of the type shown is not only extremely simple and effective, but produces sample cards of pleasing appearance, at a very low cost, with a minimum amount of waste. One of the great advantages of this type of sample card resides in the fact that the sample material may

not only be optically examined in various desirable ways, but may be touched, felt at both of its faces, or otherwise handled or tested, without requiring the removal of the sample from the support or card.

While I have described the principle of construction and the various phases of my invention, be it understood that changes and improvements may be made therein without departing from its broad scope, as set forth in the annexed claims: 10

I claim:

1. The process of producing perforated sample cards, which consists of providing in a carrier sheet two parallel rows of perforations, spaced at a predetermined distance, applying different 15 sample materials over each adjacent pair of perforations and attaching it to the body of the sheet, separating and cutting the sample-equipped carrier sheet into two individual units, so that each unit consists of one row of perforated elements, and applying and attaching each unit, with its face bearing the sample material, to a support provided with marginal perforated elements, corresponding in shape and perforations to the elements of the unit, so that the 20 25 perforations of the unit register with the perforations of the support.

2. The process of producing perforated sample cards, which consists of providing a carrier sheet with groups of perforations, each group consisting of two parallel, spaced vertical rows of perforations, the groups of perforations arranged adjacent to one another, applying over each adjacent pair of perforations of all adjacent groups, strips of different sample material, and attaching 30 it to the body of the carrier sheet, separating and cutting the now sample-equipped sheet into individual units, each unit consisting of a row of perforated, sample-carrying elements, and applying the units with their sample side to supports 35 provided with marginal, perforated elements, corresponding in shape and perforations to the elements of the unit, and so attaching the units to the supports that the elements and their perforations register with one another.

3. In a perforated sample card, spaced marginal perforated elements arranged in a row, without the sample card proper each element comprising outer covering layers and an inner sample layer held between the outer covering layers.

4. In a perforated sample card, a support provided with spaced marginal, perforated elements, without the sample card proper, a carrier, having correspondingly shaped and perforated elements, attached to said support, and a material sample 55 so secured between the elements of the support and of the carrier, that either of its faces may be touched, tested or observed from either side, or that light rays may be passed through the sample, when desired.

5. In a perforated sample card, a support, marginal sample-carrying units provided at one of its edges, outside of the sample card proper, and comprising a plurality of spaced, individual sample-carrying elements, arranged in a row, each of 65 said elements comprising two outer, perforated opaque layers, sample material held between said layers so that its major portion becomes visible within the perforations of the outer layers.

6. The process of producing perforated, multiple samples for sample cards, which consists of applying to a carrier, having rows of perforations disposed in two directions, and of which rows one consists of at least a pair of adjacent perforations, 70 75

strips of different sample material over the rows of perforations of one direction, separating the sample-equipped carrier into strips containing single rows of perforations in the other direction, 5 and attaching the strips with their material-equipped faces to a perforated backing, so that the perforations of the carrier strips register with those of the latter.

7. The process of producing perforated, multiple samples for sample cards, which consists of applying to a carrier, having rows of perforations disposed in two directions, and of which rows one consists of at least a pair of adjacent perforations, strips of different sample material over the 10 rows of perforations of one direction, attaching to the material-equipped face of the carrier a perforated backing, so that the perforations of the latter register with those of the carrier, and

separating the product into strips containing rows of perforations in the other direction.

8. In a perforated sample card, the combination with a card member, of a sample-display member conveniently attached thereto and comprising a perforated carrier, a carrier provided with a row of longitudinally arranged perforations, a backing, having similarly disposed perforations, said carrier and said backing held together so that their perforations register, a plurality of individual strips of different sample materials held in spaced relation to one another between the carrier and the backing, each strip of sample material extending from side edge to side edge of said display member and over the area of 15 one set of registering perforations.
